DEFOAMED PRODUCT

Jacob Wolfson, Irvington, N. J., assignor to
 National Oil Products Company, Harrison,
 N. J., a corporation of New Jersey

No Drawing. Original application October 18,
 1928, Serial No. 313,375. Divided and this application June 29, 1933, Serial No. 678,197

6 Claims. (Cl. 87—7)

My invention relates to defoamed products produced from those compounds and mixtures which have a tendency to foam, especially when their solution is attempted with the assistance of heat.

This application is a divisional application of my United States patent application, Serial Number 313,375, filed October 18, 1928.

There are many compounds which have the undesirable property of foaming when heated alone or when heated in the presence of substances intended to maintain them in solution or dispersion.

10 I have found that when water insoluble metallic soaps are suitably dispersed in water, such dispersions will defoam these foamable compounds or mixtures.

15 I have further found that a dispersion of such water-insoluble metallic soap can be best prepared by first dissolving the metallic soap in an organic solvent, among which are paraffin, wax, fatty acids, pine oil and kerosene, and then dispersing the solution in water with a suitable dispersing agent, among which are sulphonated oil and sulphonated tallow.

20 As an example of a method of producing one such dispersion, or defoaming agent, I give the following:— 40 parts paraffin wax and 10 parts aluminum stearate are heated until the aluminum stearate is dissolved and 50 parts of sulphonated tallow are added and the mixture is heated to about 75° C. for 15 minutes under constant stirring and allowed to cool.

25 As an example of the use of the defoaming agent, produced as above, I give the following:— Determine the amount of dry glue in a glue solution to be treated, and add to said glue solution an amount of the defoaming agent equal to two per cent of the amount of dry glue. This mixture should be made at a temperature of 60° C., and when thoroughly mixed, cooled and dried.

30 My defoaming agent does not separate from the glue as do other suggested defoamers, such as the insoluble greases.

35 The process of my invention is not limited in its application to glue and similar substances, but can be employed with valuable advantages for the defoaming of other substances, for example paper coating compounds.

40 In employing my defoaming agent to paper-making compounds, I allow a small stream of a 5% dispersion of the defoaming agent to run into the beaters connected with the paper machine. The addition of the defoaming at this point reduces the foaming in the washers at the point where the pulp is run onto the screen.

In employing my defoaming agent to paper coating mixtures, I add 1% of the defoaming agent based on the weight of the paper coating mixture to the latter. I prefer to disperse the defoaming agent in a small quantity of water before adding it to the paper coating mixture.

By "dispersed insoluble metallic soaps" I mean the dispersed insoluble metallic soaps of fatty acids, but I prefer to employ the higher melting point fatty acids, as stearic acid and palmitic acid.

Among the water-insoluble metallic soaps which I may employ in my process are aluminum stearate, magnesium stearate, calcium stearate, zinc stearate, manganese stearate and the corresponding palmitates, but I do not limit myself to these particular compounds.

In my specification and claims I do not limit myself to a single organic solvent, dispersing agent or water-insoluble metallic soap, as more than one of the members of these several groups of chemicals can be employed and I refer to them singly only for ease of expression, my invention covering them above and in combination.

I do not limit myself to the particular quantities, times, temperatures, chemicals or steps of procedure particularly mentioned and described, as these are given simply as a means for clearly describing the process of my invention.

What I claim is:—

1. A defoamed product consisting of a mixture of a foamable substance, a dispersed water-insoluble metallic soap and a sulphonated organic dispersing agent.

2. A defoamed product consisting of a mixture of a foamable substance, a dispersed aluminum stearate and a sulphonated organic dispersing agent.

3. A defoamed product consisting of a mixture of a foamable substance, a dispersed aluminum stearate and a sulphonated tallow.

4. A defoamed product consisting of a mixture of glue, a dispersed water-insoluble metallic soap and a sulphonated organic dispersing agent.

5. A defoamed product consisting of a mixture of glue, a dispersed aluminum stearate and a sulphonated organic dispersing agent.

6. A defoamed product consisting of a mixture of glue, a dispersed aluminum stearate and sulphonated tallow.

JACOB WOLFSON. 105
